US0D1038195S

(12) **United States Design Patent** (10) **Patent No.:** **US D1,038,195 S**
(45) **Date of Patent:** **** Aug. 6, 2024**

(54) **POST-CURING CHAMBER**

(71) Applicant: **SprintRay Inc.**, Los Angeles, CA (US)

(72) Inventors: **Hossein Bassir**, Los Angeles, CA (US);
Lee Hendrickson, Los Angeles, CA (US)

(73) Assignee: **SprintRay, Inc.**, Los Angeles, CA (US)

(**) Term: **15 Years**

(21) Appl. No.: **29/928,231**

(22) Filed: **Feb. 8, 2024**

Related U.S. Application Data

(63) Continuation-in-part of application No. 18/216,471, filed on Jun. 29, 2023, which is a continuation of (Continued)

(57) **CLAIM**

The ornamental design for a post-curing chamber, as shown and described.

DESCRIPTION

FIG. 1 illustrates a right-side elevated perspective view of a post-curing chamber;

FIG. 2 illustrates a right-side bottom perspective view thereof;

FIG. 3 illustrates a front view thereof;

FIG. 4 illustrates a posterior view thereof;

FIG. 5 illustrates a top view thereof;

FIG. 6 illustrates a bottom view thereof;

FIG. 7 illustrates a left-side view thereof;

FIG. 8 illustrates a right-side view thereof;

FIG. 9 illustrates a right-side elevated perspective view, showing a lid-opened state thereof; and,

FIG. 10 illustrates a right-side elevated perspective view, showing a lid-opened state thereof.

The broken lines in the drawings depict portions of the post-curing chamber that form no part of the claimed design.

1 Claim, 10 Drawing Sheets
